CLAIM

We claim the ornamental design for a gravity-operated spine stretcher, as shown and described.

DESCRIPTION

FIG. 1 is a perspective view of the gravity operated spine stretcher.

FIG. 2 is a top plan view thereof.

FIG. 3 is a bottom plan view thereof.

FIG. 4 is a side elevation view thereof, the opposite side elevation view being a mirror image.

FIG. 5 is an enlarged end elevation view thereof; and,

FIG. 6 is an enlarged opposite end elevation view thereof.

The nature and intended use of the article shown and described herein is as a gravity-assisted back stretching device.
